ROBERT E. ROBINSON AND ONE-EIGHTH TO GEORGE I. GRASTY, BOTH OF CLIFTON
FORGE, VIRGINIA.

CREEPLESS METALLIC TIE.

1,351,466.

Specification of Letters Patent. Patented Aug. 31, 1920.

Application filed May 15, 1920. Serial No. 381,724.

To all whom it may concern:

Be it known that I, LEONARD L. BROWN, a citizen of the United States, residing at Clifton Forge, in the county of Alleghany 5 and State of Virginia, have invented certain new and useful Improvements in Creepless Metallic Ties, of which the following is a specification, reference being had therein to the accompanying drawings.

10 This invention relates to creepless metallic ties, and has for its object the construction of a metal tie that is provided with means for preventing the same from creeping or moving off the road bed, and which is provided with means for receiving a crowbar to facilitate the fastening of the rail and tie together.

Another object of the invention is the construction of a tie, which will have a 20 tendency to sink into the road bed, as heavy loads pass thereover, preventing the tie from becoming center-bound.

With these and other objects in view, my invention comprises certain novel combinations, constructions, and arrangements of parts as will be hereinafter described, illustrated in the accompanying drawings, and more particularly pointed out in the appended claims.

30 In the drawings:

Figure 1 is a fragmentary perspective view of rails fastened to my improved ties.

Fig. 2 is a sectional view taken on line 2-2, Fig. 1, and looking in the direction of 35 the arrows.

Fig. 3 is a sectional view taken on line 3-3, Fig. 2, and looking in the direction of the arrows.

Fig. 4 is a sectional view taken on line 40 4-4, Fig. 2, and looking in the direction of the arrows.

Fig. 5 is a perspective view of one of the wood blocks.

Referring to the drawings by numerals, 1 45 designates the ties, and 2 the rails resting thereon. Each tie comprises a body 3, having an elongated central opening 4, that is normally filled by stone or ballast, as seen in Fig. 2. The body 3 of the tie is provided near each end with block-receiving 50 pockets 5, in which the wood blocks 6 are positioned. Overhanging the upper edges of these pockets 5 are flanges 7, which rest upon the blocks, permitting the upper face 9 (Fig. 5) of each block to lie flush with the

top-portions 8 of the body of the tie, whereby the rails 2 will rest flat upon these top-portions 8, as well as the top of the blocks, and the rails are secured to the wood blocks by the spikes 10.

Formed in the top of the tie, and preferably over a greater portion of its upper face, are transversely-positioned elongated sockets 11, constituting pockets for receiving the spurs or lugs on car-replacing devices of any ordinary structure. These replacing devices can be quickly placed upon my tie or ties, the spurs or lugs entering or engaging the elongated sockets for readily anchoring the replacing devices upon the 70 rail, as conditions may require.

Another important feature of my invention is the forming of diagonal crowbar receiving notches 12 in the top edges of the tie; these notches are arranged diagonally so that the crowbar 13 can be placed in any 80 one readily, extending under the rail and under the adjoining tie to be spiked to the rail; for instance, as shown in Fig. 1, the crowbar 13 is resting upon a tie that has already been fastened to the rails, and the outer end of the bar is resting under the adjoining or contiguous tie, holding it up against the under face of the rail, while the spike 10 is being driven, by the sledge hammer 14, into the wood block 6; the crowbar 90 is efficiently retained in the particular notch in which it is seated and will not slide or slip along the edge of the tie.

It is to be noted that the diagonally formed bar-receiving notches 12 are constructed in the edges of the tie at opposite sides of the rail or rails, the notches opening in every instance toward a rail, so that the crowbar 13, when placed in the notches, will be permitted to satisfactorily extend 100 under the rails and under the contiguous tie or ties, for enabling the operator to hold the tie securely against the rail or rails, while said tie is being fastened thereto.

It will be understood that after the tie has 105 been fastened to the rails by driving the spikes 10 into the blocks 6, the ballast can be rammed or pushed freely under the base of the blocks, as well as under the body of the tie, and as the train passes over the ties, the 110

same will be more securely seated in the road bed and should, as time passes, the ties be pressed somewhat down into the road bed, by reason of the open center structure 4 of the body of each tie, the ballast can work up slightly over the center, preventing any center binding from occurring; in other words, the tie frees itself from any undue packing at the center, permitting the tie to be always snugly and firmly, as well as properly seated in the road bed, resulting in a very efficient and satisfactory track.

The undesirable feature about "center binding" is that a train passing thereover is liable to rock the tie at its ends, causing the train to be derailed or jump the track.

The ends of the tie are provided with horizontal apertures or openings 15, for decreasing the weight of the tie, and thereby lessening the cost by not consuming as much material as it would if the ends were solid.

If I desire, I utilize horizontal apertures 16 for driving nails into the sides of the blocks 6 for temporarily holding the blocks in the tie, during the handling of the tie in the construction of a track; it is to be understood that it is optional whether these holes 16 are utilized.

While I have described the preferred embodiment of my invention, and have illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claims.

What I claim is:

40 1. A tie of the class described, comprising

a body having a free vertically-arranged central opening and with wood blocks between said central opening and its ends, crowbar receiving means formed upon the body, a replacing-device receiving or anchoring means formed upon the body.

2. A tie of the class described, comprising a body, blocks in said body near its ends, and said body provided with crowbar receiving notches opening toward the adjacent rail seats.

3. A tie of the class described, comprising a body provided contiguous to each end with crowbar receiving notches, and blocks for receiving spikes in said body contiguous to said notches.

4. A tie of the class described, comprising a body provided contiguous to its ends with blocks, and said body provided contiguous to the ends of said blocks with transversely-positioned elongated sockets for receiving portions of a car replacing device.

5. In a device of the class described, the combination with a pair of rails, of a tie extending under said rails, said tie provided with a central opening or aperture for allowing ballast to work up through the same, blocks in said tie under the rails, means fastening said rails to said blocks, said tie provided at opposite ends of the blocks and at opposite sides of each rail with a plurality of transversely-positioned sockets, and said tie provided at its upper outer edges with crowbar receiving notches, and the outer end of each notch extending toward the side of a rail, substantially as shown and described.

In testimony whereof I hereunto affix my signature.

LEONARD L. BROWN.
